UNITED STATES PATENT OFFICE.

FRANK P. GLAZIER, OF CHELSEA, MICHIGAN.

VAPOR-BURNER.

SPECIFICATION forming part of Letters Patent No. 593,015, dated November 2, 1897.

Application filed August 26, 1896. Serial No. 603,971. (No model.)

To all whom it may concern:

Be it known that I, FRANK P. GLAZIER, a citizen of the United States, residing at Chelsea, in the county of Washtenaw and State of Michigan, have invented certain new and useful Improvements in Vapor-Burners, of which the following is a specification, reference being had therein to the accompanying drawings.

10 My invention relates to oil-burners of the Bunsen-burner type; and the invention consists in the peculiar construction, arrangement, and combination of parts, as more fully hereinafter described.

15 In the drawings, Figure 1 is a vertical central section through my burner. Fig. 2 is a similar section through a double burner. Fig. 3 is a side elevation. Fig. 4 is a perspective view of the base and non-combustible wick detached. Fig. 5 is a plan of the burner shown in Fig. 1 on a somewhat reduced scale.

20 A is the base of my burner, provided with the oil-channel B in its upper face. This base I preferably make of cast metal and of annular form.

25 C is a lateral feed-pipe connecting with the channel B at one point and leading from a suitable source of oil-supply. (Not shown.)

30 Within the channel B is placed the non-combustible wick D, which is preferably formed of asbestos fiber *a*, inclosed in the perforated metallic casing *b* of U-shaped cross-section, which rests on the bottom of the channel.

35 Extending upward from the oil-channel is a perforated casing comprising the inner tube E and the outer tube F, said tubes preferably resting on the shoulders *c* on the sides of the oil-channel.

40 The tube E is preferably provided at its upper end with the cap G, having imperforate sides and an apertured top.

45 H is an imperforate casing surrounding the outer perforated tube F and secured thereto by the spiders I.

50 J are cams depending from the casing H, and K are arms projecting laterally from the base with which said cams are adapted to engage.

55 In Fig. 2 I show a construction in which the base is provided with the two annular channels B, with an air-passage between and connected together by the cross oil-channel L.

M and N are two perforated tubes preferably connected together by the spiders O and forming, respectively, the inner wall of the outer perforated casing and the outer wall of the inner perforated casing, the other walls 60 being formed by the tubes E and F.

P is a flame-passage between the two casings preferably formed as an archway on the base.

In operation the burner being suitably 65 mounted in the stove or wherever it is desired to be used it is lighted by first rotating the casing H, which, through the cams J bearing on the arms K, raises the tube F sufficiently to disclose the wick. After the 70 wick is lighted and the tube F lowered again the flame rises to the top of the perforated casing, and where the double burner is used it also passes through the passage P to the inner wick, lighting that also. At the same 75 time air is drawn in through the passages Q and R in the base and through the space between the tube F and casing H, passing through the perforations in the tubes E, F, M, and N and commingling with the vapor of 80 the oil, causing it to burn with a blue flame.

What I claim as my invention is—

1. In an oil-burner, the combination of a base cast with the central opening, an annular channel, supply-duct therefor, and laterally-extending arms K, a non-combustible wick in said channel, a stationary perforated extension of the inner wall of said channel, a movable perforated extension of the outer wall of said channel, an inclosing imperforate 90 casing secured to the outer-wall extension and having downwardly-extending cams engaging said radial arms, substantially as described.

2. An oil-burner comprising the base having concentric oil-channels formed therein and lateral oil-feed connection therewith, a non-combustible wick in each of said channels, perforated casings extending above said channels and a flame-passage between and connecting the perforated casings substantially as described.

In testimony whereof I affix my signature in presence of two witnesses.

FRANK P. GLAZIER.
